(57) **CLAIM**

The ornamental design for a chicken feeder, as shown and described.

DESCRIPTION

FIG. 1 is a top-front-left side perspective view of a chicken feeder;

FIG. 2 is a front view of the chicken feeder of FIG. 1;
 FIG. 3 is a back view of the chicken feeder of FIG. 1;
 FIG. 4 is a left side view of the chicken feeder of FIG. 1;
 FIG. 5 is a right side view of the chicken feeder of FIG. 1;
 FIG. 6 is a top view of the chicken feeder of FIG. 1; and,
 FIG. 7 is a bottom view of the chicken feeder of FIG. 1.
 The dash-dot-dash broken lines represent the bounds of the
 claim and form no part of the claimed design.
